UNITED STATES PATENT OFFICE.

ANDREW BRUBAKER, OF ASHLAND, OHIO.

DESIGN FOR A COMBINED FUNNEL AND MEASURE.

SPECIFICATION forming part of Design No. 29,377, dated September 20, 1898.

Application filed August 23, 1898. Serial No. 689,357. Term of patent 14 years.

To all whom it may concern:

Be it known that I, ANDREW BRUBAKER, a citizen of the United States, residing at Ashland, in the county of Ashland and State of Ohio, have invented and produced a new and original Design for a Combined Funnel and Measure, of which the following is a specification.

This invention relates to a new and original design for a combined funnel and measure; and it has for its object to provide a design of this character that shall be both useful and ornamental.

The leading feature of the design resides in a hollow cylindrical body of a uniform diameter from end to end and provided at the top edge thereof with an outwardly-flaring rim or flange of a sigmoidal curvature in cross-section, said body being further provided with a single offset exterior annular bead at a point near the top thereof and also at its extreme upper and lower edges.

In the drawings, Figure 1 is a perspective view of a combined funnel and measure embodying the herein-described design. Fig. 2 is a vertical longitudinal sectional view thereof.

Referring to the drawings, the numeral 1 designates the hollow body of the funnel and measure. This body is of a cylindrical shape 30 with a uniform diameter from end to end and is provided at the top thereof with an outwardly-flaring rim or flange 2. The said outwardly-flaring rim or flange 2 is provided at its upper edge with a single exterior annular 35 bead 3, and at its extreme lower edge the body is provided with a similar bead 4. In addition to the beads 3 and 4 at the extreme upper and lower edges thereof the hollow cylindrical body 1 is further provided with 40 a single exterior annular bead 5, located at a point near the top of the body.

What is claimed is—

The design for a combined funnel and measure, herein shown and described. 45

In testimony that I claim the foregoing as my own I have hereto affixed my signature in the presence of two witnesses.

ANDREW BRUBAKER.
